UNITED STATES PATENT OFFICE.

WALTER F. BARRY, OF ORANGE, NEW JERSEY.

GRINDING OR POLISHING APPARATUS.

1,254,111.

Specification of Letters Patent. Patented Jan. 22, 1918.

Application filed February 6, 1917. Serial No. 146,869.

To all whom it may concern:

Be it known that I, WALTER F. BARRY, a citizen of the United States, residing at Orange, in the county of Essex and State of New Jersey, have invented certain new and useful Improvements in Grinding or Polishing Apparatus; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to improvements in that class of apparatus adapted for use in the grinding or polishing of articles; and the present invention has reference, more particularly, to a novel apparatus which is more especially adapted for the use of dentists for grinding and polishing gold and porcelain teeth.

The present invention has for its principal objects to provide a grinding or polishing apparatus of the general character herein-after set forth, combining with a grinding or polishing wheel an inclosing casing or shell made in part or in its entirety of glass or other suitable transparent material which will permit light to traverse through the surrounding casing or shell of the apparatus, so that all portions of the grinding or polishing wheel, as well as the work which is held against the surface of the wheel, will be illuminated, and that the surrounding portions of the casing or shell will not throw objectionable shadows upon the work, to the detriment of properly and perfectly finishing the work, or to the detriment of the operator.

The invention has for its further object to provide a novel, efficient, clean and simple apparatus, the surrounding casing or shell of the grinding or polishing wheel being light, so that it can easily be placed in its operative position, or can be readily removed for the removal from the pan and the saving of the quantities of gold-dust collected therein.

The invention has for another object the use in connection with the shell or casing of the grinding or polishing apparatus, of a novel and simple arrangement and construction of lubricating means for conveying a lubricant to the grinding or polishing

surface of the grinding or polishing wheel of the apparatus; and, furthermore, to provide in connection with the apparatus an adjustable lubricant-conveying means, in the form of a wick or the like, the end-portion of which can at all times be maintained in proper contact with the grinding or polishing surface of the wheel, as it wears away with constant use, for the perfect lubrication of said grinding or polishing surface.

Other objects of the present invention not at this time more particularly enumerated will be clearly understood from the following detailed description of the present invention.

With the various objects of the present invention in view, the said invention consists primarily, in the novel grinding or polishing apparatus herein-after set forth; and, the invention consists, furthermore, in the novel arrangements and combinations of the various devices and parts, all of which will be more fully described in the following specification, and then finally embodied in the clauses of the claims which are appended to and which form an essential part of the said specification.

The invention is clearly illustrated in the accompanying drawings, in which:—

Figure 1 is a front elevation of a grinding or polishing apparatus illustrating one embodiment of the principles of the present invention; and Fig. 2 is a transverse vertical section of the same, said section being taken on line 2—2 in said Fig. 1, looking in the direction of the arrow α .

Similar characters of reference are employed in the said above described views, to indicate corresponding parts.

Referring now to the said drawings, the reference-character 1 indicates a suitable grinding or polishing wheel, mounted upon a shaft 2 which is rotatably mounted in a suitable bearing, as 3, and may be suitably driven from a driving wheel 4, or other suitable driving element. Removably disposed about the said driving or polishing wheel, by being placed upon a table or bench, as 5, or any other suitable support 105 is a casing or shell, as 6. The shell or casing consists, essentially, of a bottom-member 7, a laterally extending front-member 8, and a pair of longitudinally extending side-members 9, formed at their rear portions 110 with suitably enlarged parts or side-portions 10, said enlarged parts or side-portions be-

ing connected with each other and with the rear portion of the said bottom-member 7 by a curved or other suitably-shaped wall, as 11, substantially as shown in Fig. 2 of the drawings. The various side or wall-members of the shell or casing thus formed provide what may be termed a collecting pan which is open at its front portion and at its rear portion has an inclosing hood, all 10 of which, when made in glass, or the like, are integral so as to provide a one-piece apparatus.

Integrally united with the upper portion 12 of the said hood and extending inwardly 15 and forwardly, at an acute angle to the lower or inner surface-portion 13 of said member 12 is a tube-like element or member 14 which provides a receiver in which is telescopically disposed, for adjustment, and 20 removably arranged another tube-like element or member 15. The inner end of said member 15 is open, as at 16, and has its lower end 17 projecting from the lower open end-portion of the tube-like element or member 14. Suitably connected with the said lower 25 end 17 of the member 15 is a nozzle or other suitably shaped lubricant-conveyer, as 18, in which is disposed, in a suitable manner, a conveying means, as a wick 19, the projecting end-portion of which is in contact with the grinding or polishing surface of the grinding or polishing wheel 1, as shown. Suitably secured to the body-member of the 30 said lubricant-conveyer 18 are a number of spring-like fingers, as 20, which extend upwardly and rearwardly, and have their free ends in frictional retaining engagement or contact with the outer surface-portions of the said element or member 14, to properly 35 retain the several members in their connected as well as in their adjustable relation, and still permitting the removal or disconnection of the member 15 and its lubricant-conveyer from said member 14, as will be 40 evident. Adjustment of the wick 19 may be made by means of a wick-adjusting device, as 21, or any other means suitable for the purpose.

The lubricant usually employed may be a 50 mixture of glycerin and water, the glycerin preventing a too rapid flowing or dripping of the lubricant from the end of the nozzle. Sponge or other suitable matter, as 55 22, may be placed within the said tubular element or member 15, as shown in Fig. 2 of the drawing, for retaining the lubricant in proper quantity within said member or element, as will be understood. That portion of the said member 14 where it is united 60 with the member 12 of the hood provides a suitable inlet, as 23, for pouring the lubricant into the said element or member 15 and upon the sponges contained therein.

65 The grinding or polishing operations of the apparatus will be clearly understood

from an inspection of the drawings, and need not therefore be further described.

The device is simple in its construction, and the pan, after the grinding or polishing operation, can be readily handled and removed from beneath the grinding or polishing wheel, for cleansing purposes and for gathering up the sediment collected in the pan, from which the gold-dust or particles 75 can be reclaimed.

While I prefer to construct the casing or shell of the apparatus of glass for the purpose hereinbefore stated, I still may desire to construct the same of metal.

I am also aware that some changes may 80 be made in the general arrangements and combinations of the several devices and parts, as well as in the details of the construction of the said parts, without departing from the scope of the present invention 85 as set forth in the foregoing specification, and as defined in the clauses of the claims which are appended thereto. Hence, I do not limit my present invention to the exact arrangements and combinations of the several devices and parts as described in the foregoing specification, nor do I confine myself to the exact details of the construction 90 of the said parts, as illustrated in the accompanying drawings. 95

I claim:—

1. A grinding or polishing apparatus comprising in combination with a grinding or polishing element, a pan-shaped casing formed with a hood-shaped portion, a tubular receiving element connected with said hood-shaped portion, and a lubricant-containing element connected with said receiving element. 100

2. A grinding or polishing apparatus comprising in combination with a grinding or polishing element, a pan-shaped casing formed with a hood-shaped portion, a tubular receiving element connected with said hood-shaped portion, and a lubricant-containing element slidably and adjustably connected with said receiving element. 110

3. A grinding or polishing apparatus comprising in combination with a grinding or polishing element, a pan-shaped casing formed with a hood-shaped portion, a tubular receiving element connected with said hood-shaped portion, a lubricant-containing element slidably and adjustably connected with said receiving element, a wick-containing conveyer connected with said lubricant-containing element, a wick-adjusting means connected with said conveyer, and means connected with said conveyer and coöperating with said lubricant-containing element and with said receiving element for retaining said lubricant-containing element in its adjusted relation to said receiving element. 115 120 125

4. A grinding or polishing apparatus 130

comprising in combination with a grinding or polishing element, a pan-shaped casing formed with a hood-shaped portion, a tubular receiving element connected with said hood-shaped portion, a lubricant-containing element, slidably and adjustably connected with said receiving element, and spring fingers connected with and extending from said lubricant-containing element, said fingers having portions in slidable engagement with said receiving element for retaining said lubricant-containing element in its adjusted relation to said receiving element.

5. A grinding or polishing apparatus comprising in combination with a grinding

or polishing element, a pan-shaped casing formed with a hood-shaped portion, a tubular receiving element connected with said hood-shaped portion, a tubular lubricant-containing element telescopically mounted 20 in said receiving element, and a wick-containing element connected with said lubricant-containing element.

In testimony that I claim the invention set forth above I have hereunto set my hand 25 this 31st day of January, 1917.

WALTER F. BARRY.
